UNITED STATES PATENT OFFICE

JOHN E. MITCHELL, OF ST. LOUIS, MISSOURI

AIR-LINE HULL AND TRASH EXTRACTOR

Application filed February 16, 1929. Serial No. 340,353.

The general object of this invention is to provide a cotton cleaning machine the elements whereof operate in a substantially airtight casing, and to combine with the machine means for continuously exhausting air from the interior thereof, whereby through the medium of a suitable spout connected with the casing, the crude cotton, that is to say, the cotton mixed with bolls, hulls and trash, as delivered at the gin, may be drawn into the casing from a suitable source of supply, usually a wagon, and delivered directly to the cotton cleaning mechanism.

A further general object of the invention is to provide a cotton cleaning machine of the above character embodying in its construction a saw cylinder of open-work formation and to induce the suction within the casing by means of a suction spout or pipe projecting into the interior of the saw cylinder, whereby the crude cotton may not only be drawn into the casing of the machine and delivered to the cleaning mechanism, but dust, dirt and other impurities of small size, may be separated from the cotton by being drawn through the interstices provided in the drum of the saw cylinder and being carried out with the air from the casing.

Other objects of the invention relate to details of construction of a machine for enabling the broad objects of my invention to be accomplished, and these will be more clearly understood from the detailed description to follow.

In the handling of cotton at the gin, it is customary to spout the crude cotton from the wagons delivering the same by means of suction, and the conveying spout, at some point within the gin, is provided with a bend, and the outer side of the spout or conduit at the curve is formed of wire mesh, or other reticulated construction, whereby the air may escape and the cotton, impinging on the screen, will be stopped in its movement and ultimately fall away from the screen down through a discharge spout onto the floor of the gin or into a container for receiving same. It frequently happens, however, especially if the cotton is slightly damp, that the cotton will mat against the screen to an extent to

prevent the air from passing therethrough and an attendant is required to clean the screen at more or less frequent intervals. To avoid such matting of the cotton, as well as to assist in breaking up bolls drawn in with the cotton, breaking cylinders have been provided to rotate adjacent to the screen, but all such arrangements are, in a measure, unsatisfactory, and besides, involve the expense of additional equipment.

According to my invention, the air is separated from the cotton by passing through an open-work saw cylinder, and as various elements, such as the kicker roll, doffer brush and reclaiming saw cylinder, operate in proximity to the surface of the saw cylinder, the cotton is constantly removed therefrom and the openings in the saw cylinder can never become clogged up to an extent to prevent the free passage of air therethrough.

In the drawings—

Figure 1 is a view partly in rear elevation and partly in section of a cotton cleaning machine constructed according to my invention; and

Figure 2 is a cross-sectional view on the line 2—2 of Fig. 1.

Referring now to the drawings, the numeral 1 indicates generally the casing of the machine in which are enclosed the main elements of the cotton cleaning mechanism, comprising a saw cylinder 2, a kicker roll 3, doffer roll 4, and reclaiming saw cylinder 5. Mounted adjacent to the reclaiming saw cylinder and extending throughout the length thereof is a row of flexible members such as brushes 6. In the present arrangement, I prefer to mount adjacent to the kicker roll 3 an angle bar 7, also extending throughout the length of this roll, and operating to break up any bolls that may chance to be carried up by the kicker roll, or in any manner to get between said kicker roll and said bar. For a like purpose, I preferably mount a similar angle bar 8 adjacent to the surface of the saw cylinder 2.

Below the reclaiming saw cylinder 5, I mount a guard 9, which operates to prevent small locks of cotton from being thrown off of the reclaiming saw cylinder, or to enable

the latter to engage such locks of cotton if they are thrown off. To this end, the said guard provides a space 10 which is wider at its inlet than at its outlet, the width of the 5 space at the inlet being sufficient to receive small locks of cotton which may be carried around by but thrown off from the saw cylinder, and the width of the space at the outlet being so constricted that the reclaiming saw 10 cylinder can readily pick up loose pieces of cotton thrown from it. Between the brushes 6 and the upper end of the guard 9, a space 11 is provided through which hulls may be thrown out in the rotation of the saw cylinder. A trough consisting of converging side members 12 and 13 is located below the saw cylinder to receive hulls thrown out through the space 11, the lower ends of these side members being secured to the upper ends of 20 circular casing members 14 and 15 in close proximity to, or in contact with, the walls of which rotates a flutter wheel 16. On the opposite side of the machine from that just described, the casing provides an enclosed 25 outlet 17 for the cotton thrown off by the doffer roll 4, this outlet being formed by side members 18 and 19, to the lower end of which are secured circular casing members 20 and 21, within which is mounted a flutter 30 wheel 22, the outer ends of the arms of which rotate in close proximity to, or in contact with, the casing members 20 and 21. The casing 1, as a whole, is sealed against the 35 entrance of air, except through an ingress to be hereinafter referred to, and the purpose of the flutter wheels 16 and 22 is to permit, in the one case, hulls, and the other, cotton, to be continuously removed from the casing and at the same time, prevent entrance of air by contact of the arms of the 40 flutter wheels with the walls of their respective casings.

At the upper end, and preferably the rear side, of the casing 1, I provide an opening 45 extending substantially throughout the width of the casing, in which is hermetically secured the widened end portion 23 of a flue 24 to which flue is adapted to be secured one end of a pipe or other conduit, the other end 50 of which is applied to the cotton to be drawn into the machine. Within the casing 1 adjacent to the inner end or outlet of the head 23, I provide a gate 25 which may be adjusted to control the flow of cotton into the 55 machine.

For producing the necessary suction to draw cotton into the machine, I mount at one side of the machine, as shown by Fig. 1, one end of a relatively large pipe 26 having an 60 extension 27, preferably conical, projecting through one end of the saw cylinder and part way into the interior thereof. Air is adapted to be drawn through the pipe 26 by a suction fan, such as is usually employed 65 in gins, but which is not shown.

A leading feature of this invention is in forming the saw cylinder of open-work construction. To this end, I mount on the shaft 28 of said saw cylinder circular frame members 29 which support a series of longitudinal bars 30. Secured to and extending circumferentially about these bars and from end to end thereof are a number of circular saws 31, these saws being formed by bending up at right angles opposite edge portions of 70 a relatively long strip of metal, and then forming saw teeth in such bent-up portions. The strip thus formed may readily be placed in circular form on the bars and nailed thereto with their saw-toothed edges projecting 75 outward. The circular saws 31 are separated from each other by spaces 32 which are of sufficient width to permit the free passage of air, dirt, dust, and small particles of trash to pass into the interior of the saw cylinder, 80 but small enough to prevent the passage of cotton through said spaces. The course of the air into the machine, thence into the saw cylinder and through the pipe 26, is clearly indicated by the arrows in Figs. 1 85 and 2.

The driving mechanism for the rotating members of the machine is conventional and is clearly illustrated in elevation in Fig. 1 and by the dotted lines in Fig. 2, and need 90 not be described in detail.

In operation, power being applied to rotate the various members of the cleaning mechanism in the respective directions indicated by the arrows, and suction being set up in the 100 pipe 26, the crude or uncleared cotton will be drawn in through flue 24 and into the casing 1 of the machine, being, in a manner, distributed throughout the width of the machine by the head 23. As clearly indicated by Fig. 2, as the cotton passes into the machine, it strikes a curved portion 33 of the casing, which is imperforate, and is deflected 105 downwardly onto a hullboard 34. The lower end of this hullboard defines the size of a 110 passage 35 between it and the surface of the saw cylinder for the escape of hulls and small locks or wads of cotton which may not be engaged by the teeth of the saw cylinder 2. As the cotton is carried up by the saw 115 cylinder, any bolls carried up with the cotton will either be disengaged therefrom by the bar 8 or crushed in passing between said bar and the saw cylinder. The kicker roll 3 rotates in sufficiently close proximity to the 120 surface of the saw cylinder to knock back all hulls, bolls, and pieces of trash that may still be mixed with the cotton, so that substantially only clean cotton will pass beyond the kicker roll. This is removed from the saw 125 cylinder by the doffer roll 4 and, as previously stated, is discharged through the passage 17 onto the flutter wheel 22 and removed thereby from the casing. A distributor in the form of a belt conveyor 36, shown by dotted lines 130

in Fig. 2, may, if desired, be used to convey the cotton to the various gins or to additional cleaning machines mounted on said gins. Hulls and smaller locks or wads of cotton 5 passing through the opening 35 will fall upon the reclaiming saw cylinder 5 and as they pass under the brushes 6, the cotton will be caused to be firmly engaged by the teeth of the saws while the hulls will be thrown out 10 through the opening 11. As the cotton is carried around by the reclaiming saw cylinder it will be disengaged therefrom by the teeth of the main saw cylinder 2.

While the above mechanical cleaning operation is proceeding, dirt, dust and small 15 particles of trash and hulls will be drawn through the spaces 32 of the saw cylinder by suction and pass out through the pipe 26.

From the above description it will be seen 20 that I utilize the saw cylinder itself as the medium for separating the air from the cotton drawn in through the flue 24, and as this cylinder rotates and is being constantly cleaned by the action of the doffer roll 4, the 25 brushes of which to this end will preferably enter the spaces between the sides of the saws, it follows that the saw cylinder can never be matted with cotton, and hence the free passage of air therethrough is never interrupted. 30 It will also be seen that the direction of the cotton on entering the casing of the machine is changed by impact with the curved imperforate surface 33 and is thereby directed downwardly to the hullboard 34 and into 35 contact with the revolving saw cylinder 2. I thus avoid the use of perforated stationary surfaces, curved or otherwise, for separating the air from the cotton, and directing the course thereof, and, as stated, the free passage of air through the machine is maintained at all times.

I claim:

1. In a cotton cleaning machine, cotton cleaning mechanism including a hollow saw cylinder provided with circumferential openings between the saws, a casing hermetically enclosing the cleaning mechanism, means for drawing air through said circumferential openings into the interior of the saw cylinder whereby to create suction within the casing to draw crude cotton into the machine into contact with the cleaning mechanism, and hull-repelling and cotton-removing members co-operating with said saw cylinder.
2. In a cotton cleaning machine, cotton cleaning mechanism including a hollow saw cylinder provided with circumferential openings between the saws, a casing hermetically enclosing the cleaning mechanism, means for drawing air through said circumferential openings into the interior of the saw cylinder whereby to create suction within the casing to draw crude cotton into the machine into contact with the cleaning mechanism, and hull-repelling and cotton-removing means co-

operating with said saw cylinder, and a plurality of means operating respectively, to discharge the cleaned cotton and hulls from the machine while maintaining the seal of said casing.

3. In a cotton cleaning machine, cotton cleaning mechanism including a hollow saw cylinder provided with circumferential openings, a casing hermetically enclosing the cleaning mechanism, a suction pipe leading into the upper part of said casing, means for drawing air through said circumferential openings into the interior of the saw cylinder to create suction within said casing to draw into the machine crude cotton through said suction pipe, an imperforate guide for directing the crude cotton entering the machine into the zone of the cleaning mechanism, and means within the casing for separating the air from the cotton.

4. In a cotton cleaning machine, cotton cleaning mechanism including a hollow saw cylinder provided with circumferential openings, a casing hermetically enclosing the cleaning mechanism, a suction pipe leading into said casing, means for drawing air through said circumferential openings into the interior of the saw cylinder to create suction within said casing to draw into the machine crude cotton through said suction pipe, an imperforate curved guide for directing the crude cotton entering the machine into the zone of the cleaning mechanism, and means within the casing for separating the air from the cotton.

5. In a cotton cleaning machine, cotton cleaning mechanism including a hollow saw cylinder provided with circumferential openings between the saws, a casing hermetically enclosing the cleaning mechanism, a suction pipe leading into the upper part of said casing, means for drawing air through said circumferential openings into the interior of the saw cylinder whereby to create suction within the casing to draw crude cotton into the machine through said suction pipe, an imperforate guide for directing the crude cotton entering the machine into the zone of the cleaning mechanism, and means co-operating with said saw cylinder for removing hulls from the cotton and for removing cotton from the saw cylinder, respectively.

6. In a cotton cleaning machine, cotton cleaning mechanism including a hollow saw cylinder provided with circumferential openings between the saws, a casing hermetically enclosing the cleaning mechanism, a suction pipe leading into the upper part of said casing, a pipe projecting into one end of said saw cylinder in which suction may be created to draw air through the openings in said saw cylinder from said casing, whereby to draw crude cotton by suction through said suction pipe into said casing, an imperforate guide for directing the entering cotton into the

zone of the cleaning mechanism, the air and smaller impurities being separated from the cotton by passing through the openings in said saw cylinder, and devices co-operating with said saw cylinder for separating the 5 hulls from the cotton and the cotton from the saw cylinder, respectively.

7. In a cotton cleaning machine, cotton cleaning mechanism including a hollow saw cylinder provided with circumferential openings between the saws, a casing hermetically enclosing the cleaning mechanism, means for drawing air through said circumferential openings into the interior of the saw cylinder whereby to create suction within the casing to draw crude cotton into the machine, a hullboard the lower end of which defines the size of an opening for the escape of hulls past said saw cylinder, an imperforate guide for 15 directing the entering cotton to cause it to fall onto said hullboard, and devices co-operating with said saw cylinder for removing hulls from the cotton and for removing cotton from the saw cylinder, respectively.

25 In testimony whereof, I have hereunto set my hand.

JOHN E. MITCHELL.
